UNITED STATES PATENT OFFICE.

WILLIAM PRELLWITZ, OF EASTON, PENNSYLVANIA, ASSIGNOR TO INGERSOLL-BAND COMPANY, OF JERSEY CITY, NEW JERSEY, A CORPORATION OF NEW JERSEY.

STEEL RETAINER.

Application filed March 12, 1928. Serial No. 260,925.

This invention relates to rock drills, but more particularly to a steel retainer adapted to be attached to fluid actuated rock drills of the hammer type in which the piston reciprocates relatively to the drill steel.

The objects of the invention are to maintain the drill steel in the front head, to insure against unauthorized oscillation of the retainer from the retaining position and to strengthen the retainer at those points at which it is subjected most severely to strains upon the impact of the drill steel against the retainer.

Other objects will be in part obvious and in part pointed out hereinafter.

In the drawings accompanying the specification and in which is illustrated one form which the invention may assume in practice,

Figure 1 is an elevation of the front end of a rock drill having the invention applied thereto;

Figure 2 is an elevation of the front end of a rock drill showing another view of the retainer, and

Figure 3 is a transverse view taken through Figure 1 on the line 3—3 looking in the direction indicated by the arrows.

Referring to the drawings, the invention is shown applied to a rock drill only the front head A and a portion of the cylinder B of which is shown. These parts, together with others not shown, comprise the casing of the drill and are held in operative position by side bolts C disposed on opposite sides of the drill.

The front head A, among other functions, serves as a guide for a working implement or drill steel D which may project through the front head A to a point near the cylinder B to receive the blows of a hammer piston (not shown) reciprocable in the cylinder. A collar E is formed on the drill steel D to abut the front end of the front head for limiting the distance which the drill steel may extend into the front head A.

On opposite sides of the front head are formed trunnions F of cylindrical shape. The trunnions F are in this instance off-set with respect to the longitudinal axis of the drill and may be located in any convenient position with respect to the extremities of the front head.

In accordance with the present invention, means are provided for preventing ejection of the drill steel D from the front head

upon the impact of the hammer piston against the drill steel, and more particularly at the time when there is insufficient resistance to the cutting bit of the drill steel to maintain said drill steel in its rearward-most limiting position in the drill. These means comprise a steel retainer H which consists of a single piece of wire of square cross sectional form bent intermediate its ends to form a yoke J. The yoke J is of U-shape and partly encircles the drill steel D forwardly of the collar E at a distance sufficiently removed therefrom to permit limited endwise movement of the drill steel D.

The yoke J has integral side arms K which extend in a rearwardly direction on opposite sides of the front head A and terminate at their rearward ends in spiral springs L which act as cushioning means for absorbing the blows of the drill steel D against the yoke J. The springs L may consist of any suitable number of coils depending on the type of front head whereon the retainer is used and the position in which it is desired to mount the retainer. The inner coils O of the springs L are of such form as to snugly receive the trunnions F whereon the retainer H is pivotally mounted.

In order to lock the retainer H in the retaining position, said retainer is provided with locking portions P between the yoke J and the springs L. The locking portions P are of the same cross sectional area as the other elements of the retainer and are formed by twisting a portion of the side arms K substantially one-eighth of a turn about the longitudinal axes of the side arms. In this way corresponding corners Q of the side arms are brought to the inner sides of said side arms to lie slidably in grooves R formed in opposite sides of the front head A and preferably near the front end thereof.

By twisting a portion of the side arms in the manner described, the cross sectional area is increased at this point. This is desirable since it is at this point that the retainer contacts with the front head and is therefore subjected to severe angular stresses whenever the working implement strikes against the yoke J. Another desirable advantage of a retainer of this type constructed of square wire over retainers formed of wires of other cross sectional forms, such as round wire, is that a flat surface of the yoke is provided as a seat or abutment for the collar E of the

working implement. Furthermore, the inner coils which engage the trunnions F have a greater area in contact with the trunnions and are therefore less likely to be affected by wear.

5 During the operation of the drill, the retainer H will occupy a position in which the corners Q of the locking portions P lie in the grooves R in the front head. In this position of the side arms, the yoke J will lie 10 in the path of the collar E and, in the absence of resistance to the bit of the drill steel, will serve to prevent ejection of the drill steel from the front head, the blows of the drill steel against the yoke being absorbed 15 by the coil spring L. Whenever it is desired to change drill steels, the retainer H may be rocked to the releasing position 20 where it will be held by the gripping action of the inner coils O on the trunnions F. After another drill steel has been inserted in the front head, the retainer H may again be rocked to the retaining position.

I claim:

1. In a steel retainer for rock drills, the 25 combination of a front head having grooves in opposite sides, a drill steel extending into the front head, trunnions on the front head, a retainer comprising a piece of rectangular wire bent to form a yoke adapted to act as an 30 abutment for the drill steel, side arms on the yoke having integral spiral springs, the innermost coils of said springs being adapted to pivotally receive the trunnions, and locking portions on the side arms twisted 35 about the longitudinal axis of the side arms to enable a corner of said locking portions to lie in the grooves for locking the retainer in the retaining position.

2. In a steel retainer for rock drills, the combination of a front head having grooves 40 in opposite sides, a drill steel extending into the front head, trunnions on the front head, a retainer comprising a piece of square wire bent to form a yoke adapted to act as an 45 abutment for the drill steel, side arms on the yoke having integral spiral springs, the innermost coils of said springs being adapted to pivotally receive the trunnions, and locking portions on the side arms of the same cross sectional form as the side arms 50 but twisted about the longitudinal axes of said side arms to enable the innermost corners of said locking portions to engage the grooves for locking the retainer in the retaining position. 55

3. In a steel retainer for rock drills, the combination of a front head having grooves in opposite sides, a drill steel extending into the front head, trunnions on the front head, a retainer comprising a piece of square wire 60 bent to form a yoke adapted to act as an abutment for the drill steel, side arms on the yoke having integral spiral springs, the innermost coils of said spring being adapted 65 to pivotally receive the trunnions, and locking portions on the side arms formed by twisting portions of said side arms substantially one-eighth turn about the longitudinal axes of the side arms to enable corresponding corners of said locking portions to lie 70 in the grooves for locking the retainer in the retaining position.

In testimony whereof I have signed this specification.

WILLIAM PRELLWITZ.
